Attorney.

UNITED STATES PATENT OFFICE.

FRANCIS A. FLANEGIN, OF WASHINGTON, DISTRICT OF COLUMBIA, ASSIGNOR
TO LORENZO ALTON BAILEY AND MARY E. FLANEGIN, OF SAME PLACE.

LAMP-COLLAR.

SPECIFICATION forming part of Letters Patent No. 508,296, dated November 7, 1893.

Application filed December 22, 1892. Serial No. 456,105. (No model.)

To all whom it may concern:

Be it known that I, FRANCIS A. FLANEGIN, a citizen of the United States, residing at Washington, in the District of Columbia, have invented certain new and useful Improvements 55 in Lamp-Collars; and I do hereby declare the following to be a full, clear, and exact description of the invention, such as will enable others skilled in the art to which it appertains to make and use the same.

This invention relates to certain new and useful improvements in lamp collars and it has for its objects among others to provide an improved collar with means of securing the 15 same to the lamp bowl without the employment of plaster of paris or similar material, and whereby the collar can be quickly and easily detached or applied. The collar may be applied to lamps from which the collar has 20 been detached owing to the crumbling of the plaster of paris. A suitable packing is provided to prevent leakage. The construction is simple, cheap and efficient for the purpose for which it is designed.

25 Other objects and advantages of the invention will hereinafter appear and the novel features thereof will be specifically defined by the appended claims.

The invention is clearly illustrated in the 30 accompanying drawings, which, with the letters of reference marked thereon, form a part of this specification, and in which—

Figure 1 is a vertical section through a portion 35 of a lamp bowl with my improvement applied. Fig. 2 represents, in perspective, the parts constituting my invention, disassembled but in their relative positions. Fig. 3 is a plan of the securing means. Fig. 4 is an under plan view of the collar.

40 Like letters of reference indicate like parts throughout the several views in which they appear.

Referring now to the details of the drawings by letter, A designates a portion of a lamp bowl of known construction and provided with a neck a as seen in Fig. 1.

B is a collar having a depending flange b which should be of such a length as to receive between it and the body of the collar the neck 45 of the bowl and form a grasp thereon as seen in Fig. 1. The body portion of this collar is

threaded internally as seen and the threaded portion is preferably provided with an offset as seen at b' in Fig. 1 to limit the movement of the burner which is designed to be screwed thereinto as indicated by dotted lines in Fig. 1.

C is a cylindrical metallic part threaded exteriorly as seen in Figs. 1 and 2 and provided at its lower edge with a flange c which upon one side is extended to form a projecting lip c' as seen best in Figs. 2 and 3; this cylindrical part is also provided with notches c'' for a purpose which will soon appear.

D is a collar adapted to be sleeved loosely upon the tubular part C and is provided at 65 its lower edge with a projecting lip d similar to the lip on the part C. In practice the part D is sleeved upon the tubular part C with the lips of the two parts one upon the other upon the same side and the parts are then inserted 70 in the neck of the bowl by any suitable instrument engaging the little notches of the part C when such construction is provided and the part D is then turned so that its lip will project under and engage the under face 75 of the top of the bowl as seen in Fig. 1; the body portion of the collar is then screwed onto the threaded part of the tubular portion and the parts drawn together and the implement which held the parts C and D in place, 80 removed. In order to insure a perfectly tight joint I sometimes employ a packing ring E of any suitable material, such as fine cork or asbestos, which ring may sometimes be split so as to allow it to expand and contract. It is 85 beveled on its outer and lower edge so that its surface there closes upon and engages with the edge of the neck of the lamp bowl wedge-like thus more perfectly obstructing the passage of oil. This packing ring is placed with in the annular recess or chamber of the collar, and between the upper edge of the neck of the bowl and the top of the said recess of the collar as seen in Fig. 1. It will thus be seen that the collar can be readily applied 90 and as quickly removed; that it can be applied to bowls varying in size, and to bowls with necks of varying lengths.

The lips of the parts C and D should preferably be slightly curved to conform to the 100 curvature of the inner surface of the bowl, as seen in Fig. 1.

The notch c^2 may be dispensed with and in lieu thereof I make a lip or tooth d' depending from the outer edge of the lip on the part D to engage the finger or be engaged thereby in separating the lips within the lamp bowl. In this movement the part C remains stationary and the part D is turned. This lip d' is broad enough to project beyond the outer edge of the lip c' when the part D is sleeved upon the part C. Its outer said lip d' is of sufficient length to pass below and beyond the lip c' and then by means of the finger of the operator engaging the said tooth or lip the parts C and D are moved relatively to each other until the lip c' is at the opposite side of the bowl from the lip d and the lips c' and d will then project under and engage the under face of the top of the bowl as seen in Fig. 1.

Other modifications in detail may be resorted to without departing from the spirit of the invention or sacrificing any of its advantages.

What I claim as new is—

1. The combination with a lamp collar having a flange to embrace a neck of a lamp bowl, of a part with lip and adapted to engage the collar, and a part rotatably sleeved on the first-mentioned part and having a lip, as set forth. 25
2. The combination with a collar having a threaded portion, of a tubular part with lip and threads to engage the threads of the collar, and a part rotatably mounted on the tubular part as and for the purpose specified. 30
3. The combination with a lamp collar with flange, of a tubular part engaging the collar and having lip, the part rotatably sleeved on the tubular part and having lip, and a packing held in the recess, of the collar, as set forth. 40

In testimony whereof I affix my signature in presence of two witnesses.

FRANCIS A. FLANEGIN.
